MOTOR CONTROL FOR PRINTING
TELEGRAPHS

Howard L. Krum, Kenilworth, and Albert H. Reiber, Evanston, Ill., assignors to Teletype Corporation, Chicago, Ill., a corporation of Delaware

Application June 14, 1933, Serial No. 675,738

23 Claims. (Cl. 178—4.1)

This invention relates to systems and apparatus for operating printing telegraph machines, and more particularly to systems and apparatus for controlling remotely the operation of the driving 5 motors of such machines.

Systems for the remote control of driving motors of printing telegraph receivers have been devised in which a determined sequence of line operations result in stopping the motors at all 10 connected stations and in which, further, a different sequence of line operations will start the motors at all stations. These systems employ local circuits responsive to indirect control over the line for opening or closing a local circuit momentarily, 15 which will result in setting up a condition for starting or stopping the driving motor, which condition will continue until other signals over the line result in restoring the operating or nonoperating condition of the motor.

20 Telegraphic electrical operations are, for the most part, exceedingly short in time duration to meet the general requirement for high speed, and when a remote control operation produces a momentary condition in a local circuit, the time 25 of the local condition may be exceedingly short. It is advisable, therefore, to devise means for prolonging a momentary telegraphic condition to insure that local apparatus shall have sufficient time to operate fully. The object of this invention, therefore, is to provide means for prolonging by local control a condition which may be set up momentarily by remote control over the telegraph line.

A feature is to provide a system wherein the additional equipment which is provided for the various functions will not interfere with the ordinary purposes of the transmission of intelligence by normal operation.

A further feature is to provide a telegraph system so arranged that it may be left unattended by removing all power or signalling current from the line circuit without changing the motor control condition.

A still further feature is to provide such conditions in the local system that a telegraph current of any characteristic, either alternating or continuous, may be used to operate the local motor control apparatus.

The objects and features of this invention are such as may be obtained by the utilization of the various combinations and sub-combinations hereinafter more fully set forth, and as defined by the scope of the appended claims. These objects are attained by providing mechanical latches in a printing telegraph receiver, one of which may be

operated in response to telegraphic signals over the line, and another of which may be operated subsequently by the mechanical action of the printer in its normal printing cycle, the arrangement of the operating latches and their controlling members being such that the delay between the operations of a first latch and a second latch shall be ample to permit the full operation of the functions controlled thereby to effect the stopping of the driving motor.

While many systems provide for stopping the motor by brief interruption of the line circuit or by an extended period of interruption of the line circuit or by reversal of the polarity of the line current or by other changes in the nature of the line current, and while this invention may be adapted for such control, the system herein shown adapts a local motor control device to respond to a local circuit, which in turn is controlled by a double code of line signals comprising the combination in determined sequence of two codes normally used in the transmission of intelligence, the local circuit being modified throughout a time period beginning as a result of the operation of the second code and ending after a determined duration resulting from the consecutive operation of an orderly chain of mechanical devices.

In response to the first signal code, a mechanical condition is set up in locking manner so that it endures until after the response to the second code, and in response to the second code a mechanical operation occurs which depends jointly upon the receipt of the second code and the continuance of the condition set up by the first code and the second response is rendered stable and continuous by the mechanism of this invention, and later is terminated after a suitable time interval by further operation of the mechanism of this invention.

Equipment to be added to the printing telegraph typewriter comprises two parts, one part of which is an assembly of electrical devices which will stop the driving motor in response to a local signal impulse, and the second part of which is the apparatus for producing the local signal impulse. The present invention pertains essentially to the production of the local impulse for initiating the motor control function and the specific motor controlling assembly of apparatus may be of any preferred type such as that described in application Serial No. 622,859 for Electromagnetic devices, filed by Oscar A. Morgenstern on July 16, 1932, or such as that described in application Serial No. 595,503, for Motor con-

trol, filed by David S. Hulfish on February 27, 1932.

A better understanding of the invention may be had from the following description, taken in conjunction with the accompanying drawing wherein:

Fig. 1 shows a sectional view of a telegraph typewriter having the apparatus of this invention added thereto;

10 Fig. 2 shows a motor control device adapted to respond to the apparatus of Fig. 1;

Fig. 3 shows an alternative circuit arrangement of parts, and

15 Fig. 4 shows an alternative mechanical arrangement of the devices of Fig. 1.

In Fig. 1 the representation of a telegraph typewriter is taken from Patent No. 1,665,594, granted April 10, 1928 to Howard L. Krum, in which the mechanisms associated with this invention are as

20 follows: A set of five notched code bars 10 are adapted to be adjusted by telegraphic line signals pertaining to character codes or operating functions of the typewriter, and these are adjusted selectively to permit the response of any one of a

25 number of operating bars 11 which are transversely arranged across the bars 10 and under tension of individual springs 12 which tend to rotate them about their individual pivots 13 toward the code bars 10, against which rotation they

30 normally are restrained by a common bail blade 14 carried by a pair of rockers 15 pivoted at 16 and controlled jointly by spring 17, link 18, cam follower 19, and cam 20 upon main shaft 21. The main shaft 21 has a further cam 26 and its fol-

35 lower 27 connected by link 28 to rocker 29, pinned upon shaft 30 to which is fixed also the operating bail blade 31 and spring arm 32, the bail blade 31 being controlled jointly by spring 33 and cam 26 through the link 28. The pivot 13

40 is located upon one end of an arm 37, pivoted upon fixed pivot 38 and connected by link 39 to type bar 40, pivoted at 41 and adapted to operate a type face 42 or 43 to strike the platen 44.

45 The pivot 41 is carried by a shifting frame 47 guided by a ball race 48 and stud 49 and operated by a link 50 fixed to a rocking shaft 51.

The operation of the printing typewriter elements thus far described is as follows: The code bars 10 are adjusted by line signals and the main shaft 21 is released for one cyclic rotation in which the follower 19 operates the bail blade 14 to release all operating bars 11, which immediately are stopped by engagement with lugs on code bars 10 except that a selected operating bar 11 finds 55 aligned notches in code bars 10 and is moved by its spring 12 into those notches and into the path of the operating bail blade 31 which then is rocked by cam 26 and follower 27 to push the operating bar 11, transferring power from bail blade 31 to 60 pivot 13, thus rocking the arm 37 and through link 39 operating type bar 40 to cause type face 42 to strike platen 44 or a printing surface disposed thereon. In response to code "shift," the operating bar 11 then selected will rock the shaft 65 51 to shift the frame 47 which then is locked in its shifted position by a latch, not shown, and which carries the pivot 41 to a new position in which the operation of the type bar 40 will cause the type face 43 instead of the type face 42 to 70 strike the platen 44. The shift frame 47 remains in its shifted position until released by a further selection controlled by the code bars 10. These operations are more fully described in the patent to H. L. Krum, above identified.

75 To the apparatus above described there is

added, for the purposes of this invention, the following details: Upon the shifting frame 47 a striker 55 is fixed, and in the path of the striker 55 are arranged a closed pair of contacts 56 and an open pair of contacts 57 in such manner that while the shifting frame 47 is in its "shift" position the striker 55 will hold the contact pair 56 open and the contact pair 57 closed. Across the frame of the typewriter is positioned a rocking shaft 60 to which are fixed a striking arm 61, a spring arm 62, an operating arm 63, and a latch tooth 64, the shaft 60 being urged clockwise by spring 65 from arm 62 to the frame of the machine, and being adapted to be moved momentarily counterclockwise by the striker 66 on the arm 37. Latch 70, pivoted upon the frame at 71 and carrying latch tooth 72 is urged clockwise by spring 73 and is restrained by mechanical engagement with cam follower 19. Fixed upon the typewriter frame in position to cooperate with arm 63 is the contact pair 74 which is reversible and adjustable, as shown in Fig. 3, so that it may be installed and adjusted to be normally opened and to be closed by arm 63, as shown in Fig. 1, or normally closed and to be opened by arm 63, as shown in Fig. 3.

The operation of the added parts is as follows: When the shift frame 47 is lifted in response to the "shift" code, the striker 55 operates the contact pairs 56 and 57, opening 56 and closing 57, which is a continuing condition until restored by further operation of code bars 10. When the specific type bar 40 is to be operated, the code bars 10 are adjusted by line signals, the main shaft 21 operates follower 19 to lift 110 the blade 14 and also to release latch 70, permitting tooth 72 to pass into the path of tooth 64 and then cam 26 operates follower 27 and blade 31 which operates bar 11, arm 37, and striker 66 to engage arm 61 and move rocking shaft 60 115 to operate and close contact pair 74, at which time tooth 64 passes tooth 72 and spring 73 draws tooth 72 to restrain tooth 64 and thus to retain closed the contact pair 74 until in the further movement of main shaft 21 and cam 20 120 the cam follower 19 is restored and the latch 70 is lifted, thereby causing tooth 72 to release tooth 64 when spring 65 operates rocking shaft 60 and operating arm 63 to restore the contact pair 74. The impact of striker 66 upon arm 61 is 125 very brief, and without the latching action the contact pair 74 would be closed for a very short time interval, but as a result of the latching devices this time interval is extended throughout the time required for a relatively large angle of 130 rotation of main shaft 21 in the printing cycle of the typewriter.

The contact 74, as adjusted in Fig. 1 to be normally open, may be connected in series with the contact 57, as shown in Fig. 2, so that the circuit 135 of the two contacts may be closed only when contact 57 is closed by shift frame 47 and contact 64 is closed by arm 37 of the specific type bar 40. This arrangement is shown in Fig. 2, and is suitable for the operation of a motor control device such as disclosed in the O. A. Morgenstern application identified above. Alternatively, the contact 74 may be reversed, as shown in Fig. 3, and its members may be connected in parallel with members of the contact pair 56 as 145 shown in Fig. 3, so that the circuit of the contacts 74 and 56 will be opened only when contact 56 is opened by the shifted position of shift frame 47, and contact 74 is opened by action of arm 37 of the specific type bar 40. This con- 150

dition is shown in Fig. 3, and is suitable for operation of a motor control device as disclosed in the D. S. Hulfish application above identified.

A modification is shown in Fig. 4. The rocking shaft 60, contact pair 56, contact pair 57, and striker 55 are the parts shown in Fig. 1, and are identified by the same labels. The arm 63 also is identified in Fig. 1 where it is arranged to operate the contact pair 74, but in Fig. 4 it is arranged to operate the contact pairs 56 and 57 through mechanical cooperation with striker 55, by which a simplified electrical circuit is attained.

A rocking arm 76 is pivoted upon the frame at 77 and is urged by spring 78 into engagement with the striker 55. The arm 63 carries a finger 80, pivoted at 81 upon the arm 63 and urged clockwise by spring 82 into engagement with pin 83 fixed upon the rocking arm 76.

The operation of the modification shown in Fig. 4 is as follows: At each operation of the specific type bar 40, the rocking shaft 60 moves the arm 63 into the dotted line position which carries finger 80 to slide upon the pin 83 into its extended dotted line position, the movement of the finger 80 being thus ineffective upon contacts 56 and 57. Should the code "shift" be recorded upon the code bars 10, it will result in the movement of striker 55, which in the modification of Fig. 4 will move the rocking arm 76 into its alternative or dotted line position, thus moving the pin 83 into its alternative dotted position and moving the finger 80 into its dotted line position, in which position the members 55, 76, 80, and 83 will be held pending the receipt of "unshift" code upon the code bars 10. While the "shift" striker 55 is held shifted to hold the rocking arm 76 in its dotted position, should the specific type bar 40 be operated, the arm 63 will be operated and the finger 80 now in its vertical dotted line position will be propelled to strike the operating springs of the contact pairs 56 and 57 and to operate those contacts, in which operation the tooth 64 will pass the tooth 72 and will be restrained by the tooth 72 to maintain the contacts 56 and 57 operated until latch 70 subsequently is lifted by cam follower 19. The result, electrically, will be identical with the result attained in Fig. 1 or Fig. 3, depending upon whether contacts 57 or 56 are connected for service.

Apparatus of the O. A. Morgenstern device shown in Fig. 2 is as follows: With motors non-operating, a line circuit extends from ground 101 through battery 102, manual switch 103, typewriter operating magnets 104, relay contact pair 105, wire 106, winding of locking magnets 107, wire 108, wire 109, manual switch 110, line wire 111, stations 112 and 113 to ground 114, thus holding the locking magnet 107 energized. Operating relay 115 has an armature 116 which, when released to be retracted by its spring 119, causes its contact pair 117 to close, its contact pair 118 to close, and its contact pair 105 to open. In normal condition of idleness, as shown, the armature 116 is restrained by a latch 120 mounted upon a pivot 121 which is common to the latch 120 and armature 122 of locking magnets 107 and which is drawn toward the armature 122 by spring 123 and is restrained by lug 124 which engages armature 122. A return spring 125 is provided to draw the armature 122 away from the locking magnets 107 and in its retracted position the notch 126 in armature 122 may engage the adjacent end of armature 116 or the

armature 116 in its retracted position may engage the armature 122 to obstruct that armature against retraction. Contacts 57 and 74 are connected in series with magnet 115 and local power supply 130. The contacts 117 are connected in series with driving motor 131 and local power supply 130. Contacts 105 are connected as a shunt around the transmitting contacts 132. Contacts 118 are connected as a shunt upon the winding of the magnet 107. Stations 112 and 113 are similarly equipped.

The operation of the mechanism shown in Fig. 2 is as follows: The motor is shown in non-operating condition. By manual operation of key 110 at any station, the line circuit described will be opened, the magnets 107 at all stations will be demagnetized, spring 125 will retract armature 122 thereby lifting latch 120 to unlatch armature 116 to permit armature 116 to move into engagement with notch 126, but not to move sufficiently to operate any of its contact pairs 105, 117, and 118. Immediately thereafter the key 110 is released to close the line circuit, which reenergizes magnet 107 and draws armature 122 to release armature 116, whereupon armature 116 engages armature 122 mechanically to prevent its retraction by spring 125 and armature 116 operates contact pair 118 to shunt and deenergize magnet 107, operates its contact pair 105 to remove the shunt from transmitter contacts 132 and operates its contact pair 117 to close the power circuit of the motor 131, thus starting the motors 131 at all stations through similar operations thereat. To stop the motors 131 at all stations, any operating station by its transmitter 132 may send to all magnets 104 code signals to set the code bars 10 for the "shift" code, thereby operating and locking the contacts 57, and thereafter sending in like manner the code to operate the specific type bar 40 which will operate the contacts 74 to close and latch, thereby energizing magnet 115 and attracting its armature, thus operating its contact pair 117 to stop the motor 131, operating its contact pair 105 to shunt the transmitter 132 and operating its contact pair 118 to open the shunt of the locking magnet 107, whereby the line current from battery 102 will energize the locking magnets 107 and hold the armature 122 in the position shown in Fig. 2, thereby locking the armature 116 mechanically. All of these operations occur during the extended period of time between the operation of contact 74 by striker 66 and the unlatching of contact 64 by main shaft 21 and its cam follower 19. The line 111 may be opened for an extended period of time there will be no consumption of energy because then the circuit of magnet 115 is opened at contact pair 74, the circuit of motor 103 is opened at contact pair 117 and the circuit of magnet 107 and 104 is opened at switch 103.

In case the source of supply 130 should be alternating current, the time period provided between the operation of the striker 66 and the operation of the return of cam follower 19 will be ample to include a plurality of alternations of the current, thereby insuring operation of the magnet 105 which might not have responded had a momentary closure of the contact pair 74 occurred at the time between peaks of current and had the interval not been extended by the system of latching of this invention. Even with a direct current source 130, the magnet 115 has considerable work to do and requires a considerable time to reach its maximum magnetization,

which interval of time is assured by the system of latching of this invention.

Local control of a function of a receiving telegraph machine by the double code method, which comprises first placing the receiving device in shift position and then utilizing a normal recording function to effect a function entirely different, has been used successfully for motor control, but has required the provision of a quick-acting relay which would respond to a momentary interval produced by the second code. Where the motor control devices in themselves are such that they are not adapted to respond to an extremely short electrical impulse, it becomes desirable to supplement the control device by a sensitive relay reliably operated by the momentary signal impulse or to provide means for lengthening the signal impulse, and it is to the second alternative of this problem that the present invention is directed. In general, the invention comprises supplying a mechanical latching means for extending the mechanical condition which controls the motor stopping impulse in preference to providing an electrical condition for accomplishing an equivalent result.

The method of applying the latching means and the specific design of the latch will vary with the printer to which the device is to be applied, and although the invention has been described in connection with a specific form thereof, it will be understood that it has further applications and it is not intended to be limited in scope by the embodiment shown herein for illustration.

The invention claimed is:

1. In a telegraphic device, a code-controlled member, a power member, a latching member under control of said power member and operating to unlatch in every cycle of said power member, and a latchable member operable by said code-controlled member and cooperating with said latching member.

2. In a telegraphic device, a power member, an operating member, a selector responsive to code combinations of electrical signals to actuate said operating member, and a latching device for controlling said operating member, and operated by said power member to unlatch said operating member at every cycle of operation of said member.

3. In a telegraphic device, a code-controlled latchable member, a cyclically controlled latching member cooperating therewith and operating to unlatch at every cycle of operation of said telegraphic device, and an electric contact controlled by said code-controlled member.

4. In a telegraphic device, a latchable member, means momentarily operable for shifting said latchable member, a latch for said member when in shifted position, and cyclic means for operating said latch in every cycle of said telegraphic device to release said member.

5. In a telegraph typewriter, a power shaft rotatable in each printing cycle, an operating member operable to be shifted in a printing cycle, and a latch for engaging said operating member to delay the return of said operating member, said latch operable by said power shaft to release said operating member at the end of every printing cycle.

6. In a telegraph typewriter, a printing member, a main power shaft, and a latching device comprising a latch member operating to unlatch in every cycle of said main power shaft,

and a latchable member operable by said printing member.

7. In a telegraph typewriter, a printing member, a main shaft, latch member operating cyclically at every revolution of said main power shaft, a latchable member operable by said printing member, and an electric contact controlled by said latched member.

8. In a motor control system, a printing member, a power shaft, a latching device including a first latch member operating cyclically to unlatch at every revolution of said power shaft, a second latch member operable by said printing member, and a motor controlling device operable by said latching device.

9. In a motor control system, a printing member, a power shaft, a latching device including a first latch member operating cyclically at every revolution of said power shaft, a second latch member operable by said printing member, an electrical contact controlled by said latching device, and a motor controlling device operable under control of said contact.

10. In a motor control system, a printing train comprising a series of striking members, an electrical contact, a contact controlling member adapted to be struck and operated by one of said train members, a latch for latching said member when struck, a main shaft, and a cam on said main shaft controlling said latch to move into latching position prior to the operation of said contact controlling member and to move out of latching position subsequent to the striking of said contact controlling member.

11. In a motor control system, a printing train comprising a series of striking members, an electrical contact, a contact controlling member adapted to be operated by one of the members of said train, a latch for latching said member when operated, a main shaft, a cam on said main shaft controlling said latch at every revolution to move out of latching position subsequent to the operation of said contact controlling member, and a motor controlling device operable under control of said contact.

12. In a motor control system, a type bar, a striker associated with said type bar, a contact controlling member adapted to be engaged by said striker, a latch for restraining said contact controlling member, a main operating shaft, a first cam thereon for operating said type bar, and a second cam thereon for subsequently disengaging said latch from said contact controlling member.

13. In a motor control system, a type bar, a striker associated with said type bar, an electrical contact, a contact controlling member adapted to be operated by said striker, a latch for restraining said contact controlling member in operated position, a main operating shaft, a first cam thereon for operating said type bar, and a second cam thereon for subsequently disengaging said latch from said contact controlling member, and a motor-stop device controlled by said contact.

14. In a telegraph typewriter, a first member operable by code control, a striker associated with said first member, a second member adapted to be operated by said striker, a latch for restraining said second member in operated position, a main operating shaft, a first cam thereon for operating said type bar, and a second cam thereon for subsequently disengaging said latch from said member.

15. In a motor control system, a shift frame,

- 5 contact operable thereby, a printing member, a contact operable thereby, a motor control circuit containing said contacts, a latch for said second contact, and delay means for operating said latch to unlatch said second contact. 16. In a motor control system, a shift frame, a contact operable thereby, a printing member, a contact operable thereby, a circuit containing said contacts, a latch for restraining said second contact, delay means for operating said latch to release said second contact, and a motor control device controlled by said circuit. 17. In a motor control system, a shift frame, a contact operable thereby, a printing member, a contact operable thereby, a motor control circuit containing said contacts, a latch for said second contact, and mechanically operated cyclic delay means for operating said latch to unlatch said second contact. 18. In a motor control system, a shift frame, a first contact controlled by said shift frame, a printing mechanism, a second contact controlled by said printing mechanism, a motor control circuit containing said first and said second contacts and closable by said contacts jointly, and a mechanical latch prolonging the interval of closure of said circuit. 19. In a motor control system, a shift frame, a first contact controlled by said shift frame, a code-signal selecting mechanism, a second contact controlled by said mechanism, a motor control circuit containing said first and said second contacts and closable by said contacts jointly, a mechanical latch prolonging the interval of closure of said circuit, and cyclic means for unlatching said latch. 20. In a motor control system, a motor, a plurality of devices operable sequentially to stop said motor, means momentarily operable for shifting one of said devices to its operated position, and further means operating in every power cycle for continuing the period during which said device occupies its operated position and for releasing said latched device at the end of the power cycle. 21. In a motor control system, a motor, a plurality of devices operable sequentially to stop said motor, means momentarily operable for shifting one of said devices to its operated position, means for continuing the period during which said device occupies its operated position, and further means operable within the same cycle of selective operations for releasing said device. 22. In a motor control system, a motor, a plurality of devices operable sequentially to stop said motor, selective means momentarily operable for shifting one of said devices to its operated position, a mechanical latch for continuing the period during which said device occupies its operated position, and further means for releasing said latch within the same selective cycle. 23. In a motor control system, a motor, a plurality of devices operable sequentially to stop said motor, selective means momentarily operable for shifting one of said devices to its operated position, a latch for said device, and further means operable within the same selective cycle of operations for unlatching said device.
